US00D786579S

(12) **United States Design Patent** (10) **Patent No.:** **US D786,579 S**
(45) **Date of Patent:** **** May 16, 2017**

(54) **INSERT**

(71) Applicant: **Sage Products, LLC**, Cary, IL (US)

(72) Inventors: **David Beck**, Crystal Lake, IL (US);
Ron Cagle, Crystal Lake, IL (US)

(73) Assignee: **SAGE PRODUCTS, LLC**, Cary, IL (US)

(**) Term: **15 Years**

(21) Appl. No.: **29/576,835**

(22) Filed: **Sep. 7, 2016**

Related U.S. Application Data

(62) Division of application No. 29/527,786, filed on May 21, 2015, now Pat. No. Des. 769,019.

(57) **CLAIM**

We claim the ornamental design for an insert, as shown and described.

DESCRIPTION

FIG. 1 is a perspective view of an insert of the present invention.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a perspective view of another insert of the present invention.

FIG. 9 is a front view thereof.

FIG. 10 is a rear view thereof.

FIG. 11 is a left side view thereof.

FIG. 12 is a right side view thereof.

FIG. 13 is a top view thereof; and,

FIG. 14 is a bottom view thereof.

The ornamental design which is claimed is shown in solid lines in the drawings. The broken lines depict portions of the article that form no part of the claimed design.

1 Claim, 6 Drawing Sheets
